C. A. LEWIS

COMBINED SWINGING AND SLIDING WINDOW

Filed Sept. 7, 1926

Patented Feb. 8, 1927.

1,617,128

UNITED STATES PATENT OFFICE.

CLAUDE A. LEWIS, OF HOUSTON, TEXAS, ASSIGNOR TO AMERICAN WINDOW COMPANY,
A CORPORATION OF DELAWARE.

COMBINED SWINGING AND SLIDING WINDOW.

Application filed September 7, 1926. Serial No. 183,924.

My invention relates to windows, the sash of which is designed to swing inwardly to expose the outer side of the pane for cleaning.

5 The present invention is an improvement upon the window shown in my prior application for patent No. 115,141, filed June 10, 1926. In the prior application the window was shown with an upper sash which was 10 not slidable vertically but was pivoted to swing inwardly at the upper end.

The present invention has for its object 15 the provision of means for allowing a swinging movement of the upper sash and also to allow the sash to slide vertically relative to the window casing in the usual manner. It is also desired to improve the attachments for the sash which allow an easy adjustment of the window into any desired position, to 20 reverse the sash or to allow its removal from the casing.

Referring to the drawing herewith Fig. 1 is a broken side elevation of the window casing with the sash therein, the upper portion 25 of the casing being shown in vertical section. Fig. 2 is a side elevation of the upper sash and a broken section of the lower sash, the view being taken approximately on the line 2—2 of Fig. 3. Fig. 3 is a transverse section on the line 3—3 of Fig. 1. Fig. 4 is 30 a broken front elevation of the upper sash and its rider. Fig. 5 is a top plan view of a sheet steel embodiment of the upper rider removed. Like numerals of reference are 35 employed to designate like parts in all the views.

The present invention relates particularly 40 to the mounting for the upper sash of a window and the description will, therefore, be confined largely to the upper sash forming the subject matter of the invention. The window has the sash therein mounted to swing upon a rider which slides in channels in the casing as is now old. In the drawing 45 shown in Fig. 1 the casing has the usual window jamb 1, with a vertical channel 2 therein for the rider 3 upon which the lower sash is mounted. The said rider is preferably made of hollow metal construction, sliding 50 within the channel 2 and having sash cords 4 connected therewith in the usual manner. The said lower sash has laterally projecting pins 5 at the upper ends, said pins extending through slots 6 in the rider. 55 Said pins 5 also serve as a pivot for the

lower end of the upper sash as will be later described.

The upper sash 7 is mounted upon a rider or stile 8 which in turn is slidable within the channel 9 in the casing. The stile 8 may 60 be formed of a bar of wood, as shown in Figs. 2, 3 and 4. This strip of wood is slightly longer than the sash and extends below the sash for a short distance as seen in Fig. 4. A sash cord 10 is secured to the rider and a bent plate 11 is secured on the rider at the upper end, said plate being set flush with the face of the rider and having an inwardly extending flange 12 adapted to fit upon the upper face of the sash when the 65 sash is mounted thereon.

At the lower end of the rider 8, I have provided a plate 13 secured to the rider by means of screws 14. The plate has a forwardly extending bracket 15 thereon, projecting below the pin 5 on the lower sash. Said projection has a curved recess 16 on the forward end presented to engage with the hinge plate on the upper sash. 75

The sash has a plate 17 at its lower end 80 and a forwardly extending arm 18 thereon, the end of which is curved on the arc of a circle to fit within the recess 16 of the bracket, and the upper side is formed with a recess or slot 19 to receive the pin 5 on the 85 lower sash.

In Fig. 5 I have illustrated a stile 8' which is of sheet metal construction and the plate 13 is secured to the inner face of the stile by means of rivets 20. Its lower end is closed 90 by folding the metal, as shown by 21. This construction may be employed if desired.

In operating the upper sash with my invention employed thereon, it will be noted 95 that the sash and rider may be lowered relative to the casing without difficulty as the pin 5 on the lower sash is allowed to move upwardly out of the slot 19 in the arm on the upper sash. When it is desired to swing the upper end of the sash inwardly the sash 100 will be raised to its upper position with the arm 18 engaging the pin 5 of the lower sash so as to form a pivot therefor. The upper end of the sash may then be swung inwardly free of the rider about the pin 5 as a pivot. 105 In this movement the lower side of the arm 18 will move within the recess 16 so as to prevent the movement of the sash away from the pin 5. This prevents any longitudinal play of the sash while it is being 110

swung inwardly. When the sash has been moved into position with its upper end projecting downwardly, the hook formed at the forward end of the arm 18 may be released from the pin by moving the sash and the arm 18 upwardly. The sash may then be removed from the casing.

The advantages of this construction over that shown in my prior application for patent reside in the provision upon the sash of a movable rider or stile which allows the vertical sliding of the sash in the casing and yet permits the swinging and removal of the sash as in the previous embodiment. It will be possible with this construction to provide means to limit the swinging of the sash if desired, but as this provision is old in the art it is not here illustrated. The further advantage of this construction will be apparent.

What I claim as new and desire to protect by Letters Patent is:

1. In a window, a casing, an upper sash thereon, a rider at each side of said sash, a plate at the lower end of said rider, a bracket projecting forwardly from said plate having an arcuate recess therein, a hinge plate on said sash, an arm on said hinge plate having means engaging said recess to pivot therein, and means on said rider engaging the upper face of said sash in the manner described.

2. In a window, a casing, an upper sash thereon, a rider at each side of said sash 35 slidable in said casing, a lower sash having laterally projecting pins thereon, a plate at the lower end of said rider, a bracket projecting forwardly from said plate having an arcuate recess therein, a hinge plate on said sash, an arm on said hinge plate having

means engaging said recess and said pins to pivot therein, and means on said rider engaging the upper face of said sash in the manner described.

3. In a window, a casing, upper and lower sash, said upper sash having riders 45 slidable in said casing, a supporting plate at the lower end of each rider, a cooperating plate on said sash, said upper sash being adapted to swing relative to said supporting plate, and means on said rider to engage the upper end of the sash.

4. In a window, a casing, upper and lower sash, riders on said sash 55 slidable in said casing, means on said upper sash cooperating with means on said lower sash to allow the upper end of said upper sash to swing inwardly, and means on the rider of said upper sash to support said sash in its swinging movement.

5. In a window, a casing, upper and lower sash, riders on said sash 60 slidable in said casing, lateral pins on said lower sash, brackets on said upper sash engaging said pins to pivot thereon, and means on the riders of said upper sash engaging to support said brackets and sash.

6. In a window, a casing, upper and lower sash, riders on said sash 65 slidable in said casing, a supporting bracket at the lower end of the rider of said upper sash, a bracket on the sash engaging said supporting bracket to allow swinging movement of said upper sash, and a plate at the upper end of said rider engaging above the said sash to resist movement thereof.

In testimony whereof I hereunto affix my signature this 30 day of August, A. D. 1926.

CLAUDE A. LEWIS.
